DENTAL PRESS FOR FORMING WAX PATTERNS

Fred C. Miller, Los Fresnos, Tex.

Application September 8, 1937, Serial No. 162,934.

4 Claims. (Cl. 18—5.7)

This invention relates to a press for forming a wax pattern for use in casting a metallic backing for interchangeable teeth for either fixed or removable bridge-work, and it consists in the constructions, arrangements and combinations herein described and claimed.

It is an object of the invention to provide a press of simple construction embodying means whereby a wax pattern is formed embodying the 10 lingual anatomy of the tooth.

It is also an object of the invention to construct the press in such manner that the impression plate may be mounted in the press in one position only, thereby insuring proper registration between the die and the wax.

Additional objects, advantages and features of invention will be apparent from the following description considered in conjunction with the accompanying drawing, wherein

20 Figure 1 is a sectional view of the press, in use.

Figure 2 is a top plan view of the press foot with the impression and lock plate removed.

Figure 3 is a side elevation of the press foot.

25 Figure 4 is an end view thereof.

Figure 5 is a bottom plan view of the impression plate.

Figure 6 is a side view thereof.

Figure 7 is an end view of the impression plate.

30 Figure 8 is a top plan view of the lock plate.

Figure 9 is an end elevation thereof.

Figure 10 is a fragmentary top plan view of the wax manipulating handle.

Figure 11 is a cross section on the line 11—11 of Figure 10.

There is illustrated in Figure 1, a base 10 which may be of wood or otherwise, and of any suitable dimensions, upon one end of which there is mounted a press foot 11. The foot 11 is formed from a single blank of proper gauge metal, bent intermediate its length to form two parallel side plates 12. The lower edge of the plates 12 are bent at right angles in opposite directions, affording a substantial base 13, and to the base 13 a reinforcing plate 14 is welded or otherwise secured. The base 13 and the plate 14 are apertured to receive screws 15 for securely mounting the press foot to the base 10.

The upper edge of the plates 12 have a laterally extended flange 16 which cooperate with respective channels 17 of a lock plate 18, as will be described more fully hereinafter.

As may be seen from Figures 2 and 4, the press foot 11 is unconnected at one end, and intermediate the height of the walls 12 inturned lugs

19 are formed, the latter providing a fulcrum point for a manipulating lever 20.

An impression plate 21 is provided, in the present instance being shown as a rectangular plate of a size to snugly fit over the flange 16 of the press foot, the end portions of the plate being downwardly bent as at 22 and 23. The downturned portion 22 is of a height less than the portion 23 and is slidably received in the channels 17 of the lock plate 18; the portions 23 being of a height such that it will not be admitted through the channel. By this arrangement, the downturned portion 23 must be positioned to the forward end of the press foot, if the locking plate is to be engaged on the flanges 16. Obviously, reverse positioning of the impression plate is prevented.

The impression plate 21 has formed upon the underside thereof a well 24 for reception of impression or sealing wax 25 and this well may be 20 of any size and depth necessary for a given work.

The manipulating lever 20 comprises a handle portion 26 and a head portion 27. Upon the head 27 a wax holding block 28 is mounted by 25 a screw 28' so positioned as to present a pellet of wax supported thereon into registry with the die 29 of the impression plate. The head portion 27 has a kerf 30 adapted to engage the lugs 19, when the lever 20 is positioned between the 30 walls of the press foot.

As may be seen from Figures 10 and 11, the block 28 is composed of a pair of sections 31 and 32 laid in side by side contacting relation and secured by a rivet 33. The metal of the 35 sections along their inner edges is cut away to a point medially thereof, and when the sections are assembled, form a dove-tailed groove 34, and presenting an open slot 35 upon the upper face of the block 28.

In use, an impression is made in the wax 25, the impression plate 21 laid upon the flanges 16, the flange 23 being positioned toward the front. The open end of the lock plate is then presented so as to receive the plate 21 and the 45 flanges 16 within the channels 17 thereof. The lock plate 18 is then moved forwardly, which may be accomplished by grasping the upwardly curved lip 18', thereby securing the impression plate to the press foot 11. A pellet of wax, indicated at W in Figure 10, is laid upon the block 28 directly over the slot 35, when the lever 20 is placed between the walls 12 so as to position the block 28 directly beneath the die 29, the kerf 30 receiving the lugs 19 therein. A downward pres- 50 55

sure of the handle 26 will cause an upward movement of the block 28, forcing the wax into the die 29 and receives the impression therefrom, some of the wax being extruded into the dovetailed groove 34. The lever 20 is then removed from the press, and the wax impression on the block 28 is then removed by gently sliding the wax impression longitudinally along the slot 35 until the rib formed by extruding the wax thereinto has cleared the groove. From the wax impression thus obtained, the tooth backing may be cast in whatever material desired.

While I have shown and described a preferred form of the device, this is by way of illustration only, and I consider as my own all such modifications in structure as fairly fall within the scope of the appended claims.

I claim:—

1. A press for forming a wax pattern for interchangeable teeth comprising a support having parallel upstanding walls, the upper edges of the walls having an oppositely extended flange, a fulcrum member intermediate the height of the walls, an impression plate removably supported upon the flanges, the impression plate having a die upon its underside, a lock plate slidably engaging the flanges and the impression plate; a lever member cooperable with the fulcrum, the lever having a head member for support of a pellet of wax, and said head member having a longitudinally extended open-ended slot for receiving wax forced thereinto when the head member is moved into engagement with the die.
2. A press for forming a wax pattern for interchangeable teeth comprising a support having parallel upstanding walls, each wall having oppositely disposed foot portions, a plate member secured across the foot portions, a base secured to the plate member and foot portions,

an opposite disposed flange at the upper edge of the walls, an impression plate supported by the flanges, the plate having down-turned ends to engage the end edges of the flanges; a lock plate having inturned side flanges and an end flange spaced to slidably engage the first named flanges and the impression plate; inwardly turned lugs on the wall members intermediate the height thereof; a lever member cooperable with the lugs for swinging movements toward and away from the impression plate, the impression plate having a die upon the underface thereof, said lever having a head for support of a pellet of wax, and said head member having a longitudinally extended open-ended slot for receiving wax forced thereinto when the head member is moved into engagement with the die.

3. A press for forming a wax pattern for interchangeable teeth comprising an upwardly open-ended support means, an impression plate 20 removably supported upon the open end of the support means, said supporting means having a fulcrum intermediate its height, a lever member cooperable with the fulcrum, the lever having a head member for support of a pellet of 25 wax, and said head member being movable to engage the impression plate.

4. A press for forming a wax pattern for interchangeable teeth comprising an upwardly open-ended support means, an impression plate 30 removably supported upon the open end of the support means, said plate having a die upon its under face, said support means having a fulcrum intermediate its height, a lever member cooperable with the fulcrum, the lever having a 35 head member for support of a pellet of wax, and the head member having a slot for receiving wax forced thereinto under pressure when the head member is moved into engagement with the die.
